SPECTACLE FRAME FRONT

Ruth M. Goddard, New York, N. Y., assignor to Milton E. Brown & Co., New York, N. Y.

Application May 4, 1954, Serial No. 30,315

Term of patent 14 years

(Cl. D57—1)

Fig. 1.

Fig. 2.

Fig. 3.

Fig. 4.

To all whom it may concern:

Be it known that I, Ruth M. Goddard, have invented a new, original, and ornamental Design for a Spectacle Frame Front, of which the following is a specification, reference being had to the accompanying drawing, forming a part hereof.

Fig. 1 is a front elevational view of a spectacle frame front showing my new design;

Fig. 2 is a top plan view of the ornamentation portion of the spectacle frame front on the right side of Fig. 1 and shown removed therefrom;

Fig. 3 is a side elevational view of the ornamentation portion thereof, taken from the right side of Fig. 2; and

Fig. 4 is a side elevational view of the ornamentation portion thereof, taken from the left side of Fig. 2.

The dominant feature of my design resides in the portions shown in full lines.

What is claimed is:

The ornamental design for a spectacle frame front, substantially as shown and described.
